CLOSURE PLUG AND SEAL FOR DIVERSE
ELONGATED PIPE-CLEANING ELEMENTS

Riley R. Tubbs, Arkansas City, Kans.

Application June 7, 1948, Serial No. 31,527.

1. Claim. (Cl. 15—104.3)

1.

This invention relates to a sanitary pipe clean-out device and its principal object is to provide a device which may be attached to a branch of the usual Y fitting between the soil pipe and other sewer pipe whereby a plumber's tape or other pipe cleanout tool may be inserted into the sewer pipe without any danger of foul water or gas gushing therefrom.

This invention is in the nature of an improvement upon the sanitary pipe cleanout device shown and described in my United States Letters Patent 2,451,051 granted Oct. 12, 1948.

Sometimes the sewer pipe in a house becomes clogged to such an extent that the water will not flow through it and sometimes the water stands in the soil pipe which leads up from the Y fitting and in order to dislodge the clogged matter a cleanout tool is inserted through one branch of Y fitting into the sewer pipe and is worked back and forth therein.

In ordinary practice this branch of the Y fitting is closed by a screw plug or a screw cap which must be removed to permit the cleanout tool to be inserted, and when the level of the water in the soil pipe is higher than the Y fitting it gushes out through the open branch of the Y fitting thereby causing a great deal of annoyance and sometimes causing considerable damage.

In accordance with the present invention a cylinder is provided which is closed at its upper end with a sealing device and provided at its lower end with a threaded connection with the ferrule that is cemented in a branch of the Y fitting. Normally this branch of the Y fitting is closed by a screw plug and a rod is provided in connection with the cylinder which may be attached to the screw plug whereby the latter may be unscrewed by turning the rod, thus providing access to the Y fitting whereby a cleanout tool may be inserted through the cylinder, through the branch of the Y fitting and into the sewer pipe.

Another object is to provide a pipe cleanout device of simple and improved construction, easy to manipulate and eliminating the possibility of water or gas to escape into the room.

With these and other objects and advantages in view, this invention consists in the several novel features of construction, arrangement and combination of parts hereinafter fully set forth and more particularly defined in the appended claim.

The invention is clearly illustrated in the drawing accompanying this specification, in which:

Fig. 1 is a side elevation of a conventional Y fitting interposed between a soil pipe and a sewer pipe;

Fig. 2 is an enlarged longitudinal section taken on the line 2—2 of Fig. 1 and showing the cleanout device applied to the Y fitting, the view being shown in an upright position; and

2.

Fig. 3 is a plan of the cylinder portion of the cleanout device.

Referring to said drawing, the reference character 10 designates a fragment of a sewer pipe having a conventional Y fitting 11 secured upon its upper end, and 12 designates a fragment of a soil pipe secured in the upper end of the branch 13 of the Y fitting and extending up therefrom into the room or rooms of a building in which the soil and sewer pipes are contained.

Secured in the branch 14 of the Y fitting, as by cementing it therein, is a ferrule 15, the upper end of which is externally screw threaded as at 16, and internally screw threaded as at 17. The ferrule is provided with an internal annular shoulder 18 which functions to prevent the internal screw threads 17 from being injured when a cleanout tool is being passed through the ferrule. Threadedly mounted on the internal threads of the ferrule 15 is a screw plug 19, and upon the external screw threads 16 is normally secured a screw cap 39, (see Fig. 1) which covers and protects the screw plug 19 against injury. The screw plug is formed upon its upper end with a pair of apertured ears 21 to which an operating rod 20 may be connected as by a cotter-pin 22 as will be hereinafter explained. The rod 20 is not connected to the screw plug except at such time as the sewer pipe is to be cleaned.

A cylinder 23 is employed when the sewer pipe is to be cleaned. The upper end of the cylinder is closed by a sealing device 29 and its lower end is provided with a nipple or other connection 24 having an internally threaded neck 25, which may be screwed down upon the external threads on the upper end of the ferrule, whereby to connect the cylinder therewith. The nipple 24 or other connection may be secured to the cylinder by a threaded connection therewith or otherwise.

The upper end of the cylinder is offset outward radially to leave an annular internal shoulder 27 and upon this internal shoulder is placed a washer 28 upon which is placed the sealing device 29, here shown as comprising two metal discs 30, 31 and rubber or other compressible discs 32 therebetween, which compressible discs may be composed of a number of thin pliable discs vulcanized together. The upper end of the cylinder is internally screw-threaded to receive a screw-threaded ring 33 formed with a hexagonal or other many sided neck 34 to which a wrench or other tool may be applied in screwing the ring 33 down upon the sealing device or unscrewing it from the cylinder. When the ring is screwed down tight, a leak-proof joint is formed between the cylinder and the sealing device.

Centrally located in the discs 30, 31 are registering holes 30a, 31a of slightly greater diameter than that of the rod 20 and in the compressible disc 32 is a hole 32a of slightly less diameter than

that of the rod 20 whereby the wall of the hole 32a will closely hug the rod and prevent leakage around the same. The hole 32a is disposed in coaxial alignment with the holes 30a, 31a in the discs 30, 31. In the discs 30, 31 at one side of the center of the discs are holes 30b, 31b and in the compressible disc 32 between the holes 30b, 31b is an opening 32b here shown in the form of a slit. A flat narrow cleanout tape 35 may be inserted into the cylinder through the holes 30b, 31b and the slit 32b. The walls of the slit closely hug the cleanout tape and prevent leakage past the compressible disc 32.

The sealing device is also provided with openings through which a jointed cleanout rod may be introduced into the cylinder and into the sewer pipe. As shown the disc 30 is formed with an opening 39 and the disc 31 is formed with an opening 40. These openings, 39, 40 are disposed diametrically opposite the openings 30b, 31b and the slit 32b, and are of a diameter slightly greater than that of the jointed cleanout rod. In the compressible disc 32 is formed an opening or hole 41 (see Fig. 3) of less diameter than that of the jointed rod, whereby when the latter is inserted through the opening or hole 41, the walls thereof will hug the cleanout rod and prevent leakage around it. The opening or hole 41 is disposed at an angle of approximately 90° to the openings or holes 39, 40 whereby when the slit 32b registers with the openings or holes 30b, 31b a solid portion 42 of compressible discs is disposed between the openings 39, 40 thereby preventing any leakage through said openings. When a jointed cleanout rod is to be used, the ring 33 is unscrewed, the upper disc 30 removed and the compressible disc 32 is turned through an arc of 90°, bringing the opening or hole 41 to register with the opening 40 in the disc 31 and the other disc 30 is then placed upon the compressible disc with the opening or hole 39 in register with the holes 41 and 40 after which the ring 33 is screwed down upon the sealing device. In this position of the compressible disc, a solid portion thereof is interposed between the openings 30b, 31b thereby preventing any leakage of water through said openings.

An ordinary faucet 36 may be secured in the wall of the cylinder to which a hose may be attached when it is desired to flush out the cylinder and sewer pipe and an opening 37 may be provided in the cylinder wall which is normally closed by a screw plug 38. The screw plug 38 may be removed and a pipe may be screwed into the opening 37 and used in flushing out the cylinder. The faucet 36 may also be used to drain out any water standing in the cylinder above the inlet to the faucet.

In use the screw cap 39 is first unscrewed from the ferrule 15 and the rod 20 is fastened to the ears 21 of the screw plug 19 by the cotter pin 22. This connection may be made before the cylinder is screwed down upon the ferrule. After the cylinder has been screwed down upon the ferrule the rod 20 is rotated in a contra-clockwise direction thereby unscrewing the screw plug 19 from the ferrule, after which the rod and screw plug may be raised to the dotted line position seen in Fig. 2. The tape or the jointed cleanout rod is thereupon inserted through the proper holes in the sealing device. If the water is standing at a higher level than the cylinder, it may enter the cylinder through the ferrule 15, but it cannot escape therefrom. The cleanout tool is forced down through the opening in the

ferrule, through the opening in the branch 14 of the Y fitting and into the sewer pipe 10 wherein it may be worked back and forth in the customary manner to loosen the mass clogging the sewer pipe.

When the clogged matter has been loosened the cylinder and sewer pipe may be flushed out with clean water through the faucet 36 or through the opening 37 in the cylinder wall. After the sewer pipe has been cleaned out the tape or other clean-out tool is withdrawn and the rod 20 is lowered to bring the plug 19 into register with the opening in the ferrule and the rod is then turned in a clockwise direction thereby screwing the plug down tight, after which the cylinder is removed from the ferrule and the rod 20 detached from the plug. The screw cap 39 may now be screwed back in place on the ferrule.

While the invention has been shown and described in connection with a cleanout device for sewer pipes, obviously it has many other uses and may be used for cleaning out all kinds of pipes, whether containing water, gas or other liquids.

From the above it is apparent that I have provided a simple and efficient cleanout device and that one of several cleanout tools may be used without any danger of leakage from the cylinder.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

In a pipe clean-out device, the combination of a ferrule adapted to be secured in a Y fitting and having internal and external threads at its upper end, a screw plug threadedly mounted on the internal threads of the ferrule, a rod for rotating said screw plug detachably connected to the plug, said rod forming the support for the screw plug, when the latter is unscrewed from the ferrule, a housing having a threaded nipple at its lower end for connection with the external threads of the ferrule, said housing being closed at its upper end with a removable sealing device having two spaced metal discs each formed with a plurality of oppositely disposed differently shaped openings therein, and a pliable washer disposed between said discs, said washer being formed with openings therein corresponding to the openings in the discs and disposed at an angle of 90° with respect to each other, whereby when one opening in the washer registers with an opening in the discs a solid portion of the washer closes the other openings in the discs, said openings in the discs and washer selectively permitting a clean-out tool closely fitting the openings to extend through openings in the sealing device into the Y fitting.
